(57) **CLAIM**

The ornamental design for a 3 LED clip, as shown and described.

DESCRIPTION

FIG. 1 is a perspective view of a 3 LED clip;

FIG. 2 is a top plan view of the 3 LED clip of FIG. 1;

FIG. 3 is a bottom plan view of the 3 LED clip of FIG. 1;

FIG. 4 is a left side elevational view of the 3 LED clip of FIG. 1;

FIG. 5 is a front elevational view of the 3 LED clip of FIG. 1; and,

FIG. 6 is a rear elevational view of the 3 LED clip of FIG. 1.

The right side elevational view is a mirror image of the left side elevational view of the 3 LED clip of FIG. 4.
